UNITED STATES PATENT OFFICE.

GEORGE WILBUR WETZEL, OF MACOMB, ILLINOIS.

SILO.

1,416,534,

Specification of Letters Patent. Patented May 16, 1922.

Application filed April 28, 1921. Serial No. 465,295.

To all whom it may concern:

Be it known that I, GEORGE W. WETZEL, a citizen of the United States, residing at Macomb, in the county of McDonough and 5 State of Illinois, have invented a new and useful Silo, of which the following is a specification.

This invention relates to a silo and is more particularly directed to a novel means 10 for effecting closure of an entrance to the interior of the silo.

Heretofore, in order to gain access to the material stored in the silo and provide a passage for the removal of the material, 15 it was necessary to build an additional compartment to the silo proper which extended vertically to the full height of the structure, and which was constructed exterior to the body of the building. This compartment 20 or chamber formed a chute and was provided with a ladder in order that workmen might be able to reach the top of the silo and deliver material down the chute when desired after the silo had been filled.

25 Some form of removable partition or door extending the full length of the silo closed the chute from the silo proper. This former construction obviously necessitated building an expensive addition and likewise weakened the structure by reason of 30 the vertical opening which extended through the full height of the building, and since it is a matter of common knowledge that a building cylindrical or polygonal in 35 form without any interruptions to its contour is one of the most substantial structures that can be built, I propose to construct a silo having all the advantages of previous structures but without their 40 effects.

It is not alone an object of my invention to eliminate any additional structure to the silo, but to preserve its strength by disposing of all vertical openings in its walls 45 that would extend throughout any great portion of its height.

A further object of the invention is the provision of a new and improved door for the silo which, cooperating with the walls 50 of the same, divides the structure into a storage space for storing material, and a chute through which a person may gain access to the top of the storage space and

deliver the material to the ground for removal.

55 A further object of the invention is the provision of a new and improved door which is composed of sections, each section being hingedly mounted on the wall independently of the other sections so that 60 as the material behind a section has been removed, the section of the door may be swung back against the wall of the silo.

Another object of the invention is the provision of a new and improved bracing 65 means for each door and forming a part thereof which may be used as a ladder for reaching the top of the silo when said silo has been filled.

Still another object of the invention is 70 the provision of a new and improved sectional door which cooperates with the walls of the silo to form a chute, providing a means of entrance to the silo, and constituting a partition for separating the silo 75 into two compartments, the chute being provided with a small entrance from the exterior and a door for closing the same, thus sealing the silo from exterior influence.

80 Another object of the invention is the provision of a new and improved sectional door, each section having oppositely beveled edges at its top and bottom which cooperate in overlapping relation with the 85 edges of the adjacent sections of the door.

The invention further contemplates the provision of a new and improved hinging means for the door which not only acts as a means for swinging the doors but provides 90 a latching means for the free end of the door.

A further object of the invention is the provision of a new and improved means by which the metal parts on the door are excluded from coming in contact with the material stored in the silo.

95 The invention will be best understood from a consideration of the following detailed description taken in connection with 100 the accompanying drawing forming part of this specification, with the understanding, however, that the invention is not confined to any strict conformity with the showing in the drawing, but may be changed 105 and modified so long as such changes and

modifications mark no material departure from the salient features of the invention as expressed in the appended claims.

In the drawings:—

5 Fig. 1 is a view in elevation of the silo.

Fig. 2 is a vertical section of the silo disclosing the sectional door which provides a chute within the silo.

Fig. 3 is a transverse section of the door.

10 Fig. 4 is an elevation of a section of the door showing the combined hinging and latching means and the bracing means which are adapted to be used as the rungs of a ladder.

15 Fig. 5 is a fragmentary view of the door in cross section, detailing my improved hinging means.

Fig. 6 is a fragmentary view of the other end of the door in cross section detailing 20 my improved manner of employing the other end of the hinge as a latching means.

In the drawings, 1 designates the base or foundation of a silo; 2, a wall, which may be of any geometrical design, such as cylindrical or polygonal; 3, the roof; and 4, an opening formed in the lower portion of the wall to provide an entrance to the body of the silo. To the interior of the wall 2 are secured a hinge jamb 5 and a latch jamb 30 6, in any manner, as by bolts 7. The bolts either have one end embedded in the walls or pass through perforations in the walls. These jamb, which are made in suitable lengths and may be of cypress, tile or 35 cement, have a groove 8 running longitudinally in that portion which is secured to the wall and which groove is filled with cement 9 in order to provide an air-tight joint between the wall and jamb.

40 The door is composed of a number of sections 10. Each section is formed by bolting to semi-cylindrical hinge plates 11 a series of tongue and groove staves 12 and braced by rods 13 which are bolted to the 45 interior of the semi-cylindrical section by the bolts 14. One end of the hinge plate has an eye 15 adapted to be hingedly mounted on a pin 16 which is secured into the hinged jamb 5. The other end of the 50 hinge plate is bent inwardly, as at 17, from the free end of the door and provided with a slot 18 which is adapted to receive the staple 19 secured in the latch jamb 6. A chain 20 fastened on the door and provided 55 with a hook 21 at its other end engages the staple to prevent the locking means from being disturbed.

It will be noted from an inspection of Figs. 3 and 5 that the portion of the hinge 60 which is pivoted upon the pin 16 rests partly within a recess 22 in the door frame and partly within a recess 24 of the hinge jamb 5, in order that that portion of the hinge will be protected from the material in the 65 silo. The free end of the door seats snugly

within a longitudinal groove 23 formed in the latch jamb 6.

The top and bottom of each section of the door are oppositely beveled to engage in overlapping relation the beveled edges of the adjacent doors. These sections of the doors are in vertical alinement, and as the hinged portion of the sections of the door fit within the longitudinal slot 24 of the hinge jamb 5, the free end of the door fits 70 within the longitudinal slot 23 of the latch jamb 6 and the oppositely beveled tops and bottoms of the sections engage in overlapping relation with the beveled edges of the tops and bottoms of the adjacent doors, 75 80 there will be provided an air-tight seal when the material stored in the silo presses outwardly against the doors to firmly lock the sections of the doors in position.

The greater the pressure in the silo, the 85 more securely will the doors engage the wall and insure a tight closure. By supplying a door at the bottom of the silo to effect a closure of the entrance 4, a thoroughly sealed and substantially air-tight silo is 90 provided. A port 25 formed between the roof and the wall provides means of ventilation for the silo.

An opening 26 enclosed by the glass doors 27 provides a means for filling the silo. 95

In order to fill the silo all the doors are opened and placed against the inside of the wall except the bottom door. Sufficient material is delivered to the silo through the opening 26 and tamped until the material reaches the level of the top of the first section, when the second section is closed, and again material is filled in through the opening 26 until the level of the top of the second section is reached, and so on the filling is 100 continued until the whole silo is full. The pressure within securely holds the doors in position. In order to remove the contents, a workman gaining access to the interior of the chute by means of the entrance 4 will climb the brace bars 13, which act in a novel manner as rungs, to reach the top of the silo. He will throw off from the interior of the silo down the chute sufficient material until he is permitted to open the uppermost 110 section of the door which he swings back against the wall. Then the contents of a second section is removed from the chute, and so on until the contents has been entirely removed.

115 120 What is claimed is:—

1. A silo, comprising an outer wall, an opening in said wall, and an inwardly swinging door for said opening comprising a series of sections hingedly mounted on and cooperating with the wall of the silo to form an auxiliary chamber within the silo.

2. A silo, comprising an outer wall, an opening in said wall, and a door for said opening comprising a series of inwardly 125 130

- swinging sections hingedly mounted on and cooperating with the wall to form an auxiliary chamber within the silo, and means on said door sections for bracing the same, said 5 means being adapted to provide a way for climbing to the top of the silo, the hinged mounting of the sections of the door adapted to support the sections in open position.
3. A silo, comprising an outer wall, an 10 opening in said wall, an inwardly swinging door for said opening comprising a series of sections hingedly mounted on and cooperating with the wall to form an auxiliary chamber within the silo, the hinged 15 mounting of said door sections adapted to support the same in open position, and means for locking the free ends of the sections to the wall.
4. A silo, comprising an outer wall, and 20 an opening in said wall, an inwardly swinging sectional ladder hingedly mounted on the wall of and within the silo and forming a partition for dividing the silo into compartments, the sections of the ladder adapted to be held firmly in position by pressure 25 of silage within the silo.
5. A silo, comprising an outer wall, an opening in said silo, a series of substantially semi-circular inwardly swinging frames in 30 vertical alignment and hingedly mounted on the wall, said sections dividing the silo into two compartments, the hinged mounting of said frames adapted to support the frames in open position.
35. 6. A silo, comprising an outer wall, an opening in said wall, an inwardly swinging door comprising a series of sections in vertical alignment and substantially semi-circular in cross section hingedly mounted 40 on the inner portion of the wall, and bracing members for said doors forming a ladder.
7. A silo, comprising an outer wall, an opening in said wall at its lower end, a door comprising a series of inwardly swinging 45 sections in vertical alignment and hingedly mounted on the wall, said sections when closed cooperating with the wall to form an auxiliary chamber within the silo and adapted to close communication between the 50 silo and its exterior, the hinged mounting of the sections being adapted to support the sections in open position.
8. A silo, comprising an outer wall, an opening in said wall, door jambs secured on 55 said wall running the full height of said wall, means for sealing said jambs to the wall, a series of doors in vertical alignment hingedly mounted on one of said jambs, the free end of said doors being adapted to be 60 locked on the other jamb, said doors cooperating with the inner wall of the silo to form an auxiliary chamber within the silo and provide a passage to the interior of said silo.
65. 9. A silo, comprising an outer wall pro- vided with a roof, an opening in said wall, a door for said opening, strap hinges secured on the doors, one end of which forming a pivotal connection between the door and the wall, the other end of said hinges forming 70 a latching means for the free end of the door, said door being so spaced from the wall of the silo as to form an auxiliary chamber within the silo.
10. A silo, comprising an outer wall and 75 a top, an opening in said wall, a door for said opening comprising a series of hinged sections in vertical alignment adapted to divide the silo into separate chambers, each door section having its upper and lower 80 edges beveled to engage the beveled edges of the adjacent sections, and brace bars mounted at spaced intervals on each section of the door and adapted to form a ladder, the cooperating beveled edges of the 85 adjacent doors, when said doors are in closed position, presenting an unbroken surface upon both sides of the aligned doors.
11. A silo comprising an outer wall, spaced jambs provided with grooves and 90 secured to the inner surface of said wall, a door comprising a series of sections hingedly mounted on one of the jambs, the pivotal portion of the hinge being seated within the grooves in one of the jambs, the 95 free ends of the sections of the door being adapted to fit into a groove in the other jamb.
12. A silo comprising an outer wall hav- 100 ing an opening therein at the bottom, vertical jambs provided at opposite sides of said opening on the inside of said wall and extending to the top of the silo, and a door comprising a series of superposed sections arranged within the outer wall, each section 105 being curved and having a hinged connection with one of said jambs and a detachable lock connection with the other jamb, said door defining an auxiliary chamber within the walls of the silo, access to which chamber 110 may be obtained at either the top or bottom of the silo.
13. A silo comprising an outer wall hav- 115 ing an opening therein at the bottom, vertical jambs provided at opposite sides of said opening on the inside of said wall and extending to the top of the silo, said jambs being each provided with vertical recesses, and a door comprising a series of superposed sections arranged within the outer wall, 120 each section being curved and having a hinged connection with one of said jambs and a detachable lock connection with the other jamb, the outer edges of each section being seated in the recesses of said jambs, 125 said door defining an auxiliary chamber within the walls of the silo, access to which chamber may be obtained at either the top or bottom of the silo.
14. A silo comprising an outer wall hav- 130

ing an opening therein, door jambs secured to the interior of said wall at opposite sides of said opening and extending from top to bottom of the wall, a door arranged on the 5 interior of said wall and defining an auxiliary chamber within said outer wall, said door being formed of superposed sections, and each section being composed of staves secured to hinge plates extending through-

out the length of each section, means for 10 hingedly connecting one end of each plate to one of the jambs, and means for detachably connecting the other end of each plate to the other jamb.

In testimony that I claim the foregoing 15 as my own, I have hereto affixed my signature.

GEORGE WILBUR WETZEL.
